UNITED STATES PATENT OFFICE.

NILS M. ROSENDAHL, OF WATERLOO, IOWA, ASSIGNOR TO CONSTRUCTION MACHINERY COMPANY, A CORPORATION OF IOWA.

MEASURING TANK.

Application filed June 27, 1927. Serial No. 201,762.

This invention relates to tanks, and has special reference to one designed particularly for holding an intermittent water supply for concrete mixers.

5 The principal object is to provide an exceptionally simple and efficient tank of this character, and one that may be readily adjusted for furnishing the various quantities of water within its capacity.

10 Another object is to provide such a tank that is quick of action, as required for best results in concrete mixers.

15 Other objects and advantages of the invention will appear in the further description thereof.

Referring now to the accompanying drawing, forming part of this application, wherein like reference characters indicate like parts:

20 Figure 1 is a transverse sectional view through the tank, centrally of the supply pipe connection, illustrating the latter in section, as well as a portion of the discharge nozzle; and

25 Figure 2 is a perspective view of the tank and its various connections.

1 represents an elongated cylindrical tank, supported horizontally in any desired manner adjacent the mouth of a mixer or other 30 device in which the water supply is to be used; the mixer not being illustrated in this instance, as it does not form part of my present invention.

In the bottom of the tank and preferably 35 adjacent the center thereof is installed a coupling indicated at 2, which carries upon its upper and larger end internally of the tank the inverted frusto-conically shaped valve seat 3, and in its lower reduced end 4 is screw 40 threadedly attached the water supply pipe

5. A combination valve and float stem 6 is installed within the coupling 2, it having a lowermost bearing as indicated at 7, and an uppermost bearing 8, so as to be normally held in a firm upright position and free to 45 reciprocate vertically. A valve 9 is attached to the stem within the coupling 2 for intermittent contact with the valve seat 3, and a float 10 is adjustably mounted upon the

50 stem, the extended hub 11 of which is provided with the set screw 12 permitting of such adjustment upon the stem 6. Intermediate of the set screw 12 and about the central hub portion 13 of the float 10 is attached the short arm 14 of the L-shaped in-

dicator lever 14—15, the latter portion of the lever extending vertically through the collared opening 16 in the tank directly above the intake connection 2; the collar being illustrated at 17. Upon the arm 15 60 of the L-shaped lever are preferably figures, as indicated at 18, to one side of which are provided rather prominent dots or other forms of markings 19; these being so arranged as to properly indicate the contents 65 of the tank as the float is raised and lowered thereby. As the float is adjustable vertically upon the spindle 6 it is obvious that the quantity of liquid intermittently admitted to the tank may be governed thereby 70 so that any desired number of gallons, for instance, within the capacity of the tank, may be used as a charge in establishing uniformity of mixture of the concrete aggregate or the like.

75 The discharge thimble of the tank is illustrated at 20, and for convenience protrudes somewhat at an angle from the bottom of the tank, though positioned to entirely drain same, and to the outboard end of this nipple 80 is attached a nozzle 21 in which is pivotally mounted upon the shaft 22 journalled within said nozzle the check valve 23, it engaging when closed the annular seat 24 within the nozzle. The shaft 22 of the check valve extends horizontally parallel with the tank to a suitable position for convenient access by the operator, where it is provided with a control lever 25. Just above this control 85 lever and engageable thereby is the vertically reciprocable rod 26, supported in any desired manner and attached at its uppermost end 27 to the lever 28, fulcrumed as at 29 at the edge of the collar 17 about the opening 16 in the tank, the short end of said lever 90 extending to a position centrally over the collar where it becomes engageable with the extreme upper end of the intake valve controlling rod 6 when the longer end of the lever is raised by the action of the rod 26 95 100 when engaged by the lever 25.

105 Thus is it seen that, assuming there is pressure on the water supply pipe 5 and the valve 9 is closed upwardly against the seat 3 it will there remain by such pressure until the rod 6 is forcibly depressed, and this takes place only when the lever 25 is raised to its extreme uppermost position. Immediately upon the depressing of the rod 6 which unseats the valve 9, water will escape thereabouts into 110

the tank, the weight of the rod 6 being sufficient to hold the valve 9 in its open position, while the float 10 and indicator arm will be raised or lowered by the action of the water 5 within the tank, until its upward limit is reached, the same being controlled by its position on the rod as previously described.

Normally the check valve 23 remains closed, both by the pressure of the water 10 thereupon and the gravitating effect of the operating lever 25, but instantly upon the raising of this lever the valve 23 will be raised and the contents of the tank rapidly discharged into the mixer; the nipple 20 and 15 the size of the nozzle being made comparatively large for quick emptying of the tank to expedite operation of the mixer. On a further raising of the lever 25 which also becomes necessary the intake valve 9 is unseated and the tank again allowed to fill; the 20 lever 25 and valve 23 automatically assuming their closed position.

Having thus described my invention, what

I claim and desire to secure by Letters Patent, is:

1. A tank of the class described comprising a receptacle, an intake valve, a discharge valve, an indicating float cooperatively connected with the intake valve, and single means for control of the discharge valve and optional control of the intake valve. 25

2. A tank of the class described comprising a receptacle, an intake valve, a discharge valve, an indicating float adjustably mounted upon the intake valve, and single means for initial control of the discharge valve and subsequent control of the intake valve. 30

3. A tank of the class described comprising a receptacle, an intake valve, a discharge valve, an indicating float cooperatively connected with the intake valve; and single means for the optional control of one or both valves. 35

In testimony whereof I affix my signature.

NILS M. ROSENDAHL.
